UNITED STATES PATENT OFFICE.

OSCAR J. WATTS, OF KENSINGTON, KANSAS.

PENCIL OR PEN HOLDER.

1,052,702.

Specification of Letters Patent. Patented Feb. 11, 1913.

Application filed November 30, 1910. Serial No. 594,963.

To all whom it may concern:

Be it known that I, OSCAR J. WATTS, a citizen of the United States, residing at Kensington, in the county of Smith and State 5 of Kansas, have invented certain new and useful Improvements in Pencil or Pen Holders; and I do hereby declare the following to be a full, clear, and exact description of the invention, such as will enable others 10 skilled in the art to which it appertains to make and use the same.

This invention relates to improvements in pencil or pen holders.

The principal advantage of this holder is 15 that the spring members which engage with the article on which the pen or pencil is to be held are pivoted, and may thus be swung through any angle. Because of this feature the holder may be used to hold a pen or pencil 20 in a pocket, where the clip will necessarily be parallel to the pen or pencil, or it may be swung at right angles to the pen or pencil, and thus fasten it along the side of a note book, check book, purse, or other article. 25

With the above and other objects in view, this invention resides in the novel features 30 of construction, formations, combinations and arrangements of parts to be hereinafter more fully described, claimed and illustrated in the accompanying drawings, in which—

Figure 1 is a perspective view of the device, with the clips swung at right angles 35 to the pencil for attaching to a book; Fig. 2 is a perspective view showing the device attached to a pocket; Fig. 3 is a perspective view of the device separated from the pencil, and Fig. 4 is a longitudinal section 40 through the device.

Referring to the drawings by characters of reference, the numeral 1 represents the spring pen or pencil engaging member, formed from a sheet of metal having sufficient elasticity to grasp the pen or pencil 45 and hold it firmly. Two arms 2 and 3 are fastened together at their ends by a rivet, or other suitable fastener 4, the opposite ends being separated and formed so as to slip over a pocket, cover, or other article and 50 firmly hold the same within the grasp of the two arms, said arms being pivoted at an intermediate point to the pen or pencil retaining member 1 by means of a rivet 5, or any other suitable means. 55

The arm 3 is off-set toward the clip 1 adjacent to the pivotal point 5 thereof and below said off-set portion rests normally parallel to the arm 2, which is straight.

Having thus fully described this invention, what I claim as new and desire to secure by Letters Patent is:

In a pencil holder, a straight arm, a second arm riveted to the first arm at one end thereof and offset midway of its length to 65 bring the free end of the second arm in parallel spaced relation to the free end of the first arm, a pencil clip pivotally attached to both arms between the riveted extremities of said arms and the offset portion of the 70 second arm, the back of the clip being directed outwardly to enable the clip to swing across said second arm and offset to hold a pencil out of contact with said second arm.

In testimony whereof I affix my signature 75 in presence of two witnesses.

OSCAR J. WATTS.

Witnesses:

C. V. EBERSTEIN,
WALTER BOYD.
